PUNCH SET APPARATUS HAVING PUNCH MOUNTED IN VERTICALLY SPACED GENERALLY HORIZONTAL PLATES

Emanuel F. Paxhia, Tonawanda, Raymond J. Metzger, Cheektowaga, and Lynn G. White, Kenmore, N. Y., assignors, by mesne assignments, to Toolset, Incorporated, Buffalo, N. Y., a corporation of New York

Application January 4, 1954, Serial No. 401,961

9 Claims. (Cl. 164—94)

This invention relates to punching apparatus for perforating metal sheets or for performing analogous punching operations on sheet metal or like material.

Where a number of perforations or similar formations are to be made in a sheet of metal or like material by means of a conventional punch press the punching apparatus generally comprises a die assembly and a punch assembly, the die assembly being fixed to the bed of the punch press and the punch assembly being secured to a reciprocating ram of the punch press for movement toward and away from the die assembly to perform perforating or other punching operations.

Means are generally provided for guiding the punch assembly with respect to the die assembly, generally in the form of guide pins or the like. In positioning die sets of this general nature it is necessary to secure the die portion of the assembly to the bed or bolster plate of the punch press and also to secure the punch assembly to the reciprocating ram member of the punch press. These companion assemblies must of course be secured to the bed of the press and the ram of the press in proper vertical alignment to secure accurate punching relationship therebetween and to avoid binding of the guide pins in performing their guiding function. This aligning and securing procedure is delicate and time consuming and errors occurring in setting up may result in costly damage to the die, the punch press or both.

More recently it has been common practice to employ unitary punching devices which include both the punching and the die members in a single structural frame securable to the bed of a punch press, the punching member being merely engaged or impinged against by the ram of the punch press in effecting punching operations. This eliminates the necessity for accurately assembling members against both the bed of the press and the movable ram of the press in proper punching alignment but the general practice in using devices of this type has been to arrange a number of perforating units upon the bed of the press in the desired relationship with respect to each other, either by the use of templets or by individually laying out and setting up the units to produce the desired pattern of perforation or other punching formations.

The present invention provides an apparatus wherein a die assembly and a superposed punching assembly are arranged to be guided vertically relative to each other but wherein the vertically movable punching assembly rests directly upon the die assembly and is supported entirely thereby without the necessity for any securing to the vertically moving ram of the punch press with which the apparatus is associated. Thus, the apparatus of the present invention provides means whereby the punch and die units are freely movable relative to each other and are readily separable as in the case of old prior art die sets, while at the same time eliminating the necessity for securing the punching portion of the apparatus to the vertically movable ram of the punch press.

Furthermore, the apparatus of the present invention provides individual interchangeable punch and die units

2

which may be used in various supporting die sets of the type contemplated by the present invention and may also be used in individual unit perforators of the kind described generally above.

5 Many other objects and advantages resulting from the use of the punching apparatus of the present invention, from the standpoint of facility of manufacture and convenience and economy of use, will appear to those skilled in the present art from a consideration of the punching apparatus which is shown in the accompanying drawings and described in detail in the following specification. It is to be understood, however, that such apparatus is set forth herein by way of example only and that many modifications therein may be effected, particularly from 15 the standpoint of the arrangement of desired perforations and the type and size of sheets to be perforated or otherwise punched thereby. Nothing in the following specification is to be deemed as limiting the present invention to the form set forth herein by way of example and the scope of the present invention is limited only as defined in the appended claims.

In the drawing:

Fig. 1 is a general top plan view of one form of the punch and die apparatus of the present invention;

25 Fig. 2 is an irregular cross-sectional view on the line II—II of Fig. 1; and

Fig. 3 is a detailed fragmentary cross-sectional view on the line III—III of Fig. 1.

Throughout the several figures of the drawings like characters of reference denote like parts and, speaking generally and referring particularly to Fig. 2, a relatively stationary horizontal die plate is designated 10 and is adapted to be positioned upon the bed or bolster plate of a punch press. The principal structure of the punch holding portion of the apparatus comprises an upper plate 11 and a lower plate 12 which are fixed to each other in vertically spaced relationship as by means of variously disposed spacer blocks 13, 14 and 15, all of which are screwed respectively to the upper and lower plates 11 and 12 as indicated by way of example at the left-hand side of Fig. 2 in conjunction with spacer block 13.

The assembly comprising plates 11 and 12 is guided for vertical reciprocation relative to die plate 10 by means of a pair of vertical guide pins 17 and 18, one of which is shown in cross sectional detail in Fig. 3. As there shown, a guide pin bushing 19 is press fitted into plates 11 and 12 to receive guide pin 17 for vertical reciprocation. A similar bushing 20 is provided for receiving guide pin 18.

50 Die plate 10 is supported in upwardly spaced relation relative to the bed or bolster plate of a punch press, in the present instance by means of a pair of rails or blocks 21 and 22 which are parallel to each other and extend fore and aft of the apparatus with respect to the position which it normally occupies in a punch press. The die plate is supported on blocks 21 and 22 to provide a clear scrap clearance and disposal space beneath the die plate 10. In the form shown herein by way of example the guide pin bushings 19 and 20 are pressed jointly into die plate 10 and the underlying supporting rails or blocks 21 and 22, as clearly shown in Fig. 3.

The punch holding assembly is normally held resiliently in upwardly spaced relation relative to die plate 10 by means of lifter springs 24 and 25, one of which is shown in Fig. 2. Referring to Fig. 2, lifter spring 24 seats at its lower end in a recess in die plate 10 and its upper end surrounds a pin 27 which is pressed into the lower plate 12 of the punch holding assembly.

Reference will now be had to the punching devices themselves, the die portions of which are supported in die plate 10 and the punching and stripping portions of which are jointly supported in the punch plate members

11 and 12. In the present instance a plurality of punch and die assemblies are provided which are designated generally by the numerals 30 through 36 in Fig. 1. While these punch and die assemblies are for perforating holes of varying diameters, the details of their construction are uniform excepting for such size differences and a description in detail of the punch and die assembly designated generally by the numeral 34 will suffice for all. The details of punch and die assembly 34 are shown in cross-sectional detail in Fig. 2.

A hardened steel die bushing 38 is set into a recess in the upper surface of die plate 10 and the latter is provided with the usual scrap clearance hole extending from the bottom of die insert 38 to the bottom of die plate 10. The punch assembly includes a punch member proper designated 40 provided with a generally cylindrical head member 41 which in the present instance is screwed to the upper end of punch element 40 as at 42. Head member 41 has vertical sliding bearing in upper plate member 11 of the punch holding assembly.

Punch element 40 is surrounded adjacent its lower portions by a stripper sleeve member 44 which is of general cylindrical form and provided with an enlarged upper portion which seats against a companion shoulder provided in the bore in punch plate 12 which is adapted to receive the stripper bushing 44. Head member 41 is provided either with a flattened side portion or with an intermediate portion of reduced diameter, as at 46 in Fig. 2, and a retaining plate member 47 is screwed to the top of punch plate element 11 as at 48.

The edge of retaining plate member 47 engages the reduced diameter portion of head member 41 and limits upward movement of the latter. A stripper spring 49 surrounds the intermediate portion of punch element 40, bearing at its lower end against the upper end of stripper sleeve 44 and at its upper end against the bottom of head element 41, to urge the latter into an upper limit position as determined by retaining plate 47.

In Figs. 1 and 2 the numeral 50 designates a plurality of gage pins for locating a worksheet 51. However, it is to be understood that the shape and size of the worksheet and the number, size and location of the perforations to be made therein will vary widely.

What is claimed is:

1. Sheet material punching apparatus for use in a punch press having a die receiving bed and a ram reciprocable toward and away from said bed, said apparatus comprising a die plate member securable to said bed and a punch holding member comprising a pair of vertically spaced generally horizontal plates, vertical guide pins fixed to one of said members and slidably engageable with the other, compression spring means acting between said members to normally retain the punch holding member in an elevated position, a plurality of punching units each comprising a stripper sleeve carried by the lower plate of the punch holding member, a punch extending through said stripper sleeve and having an enlarged upper head portion vertically slidable in the upper plate of the punch holding member and projecting thereabove to be engaged by said reciprocable ram, and a compression coil spring surrounding the punch and engaging at its upper end against said punch head portion and at its lower end against the stripper sleeve.

2. Sheet material punching apparatus for use in a punch press having a die receiving bed and a ram reciprocable toward and away from said bed, said apparatus comprising a die plate member securable to said bed and a punch holding member comprising a pair of vertically spaced generally horizontal plates, means guiding said members for movement toward and away from each other, compression spring means acting between said members to normally retain the punch holding member in an elevated position, a plurality of punching units each comprising a stripper sleeve carried by the lower plate of the punch holding member, a punch extending through said stripper

sleeve and having an enlarged upper head portion vertically slidable in the upper plate of the punch holding member and projecting thereabove to be engaged by said reciprocable ram, and a compression coil spring surrounding the punch and engaging at its upper end against said punch head portion and at its lower end against the stripper sleeve.

3. Sheet material punching apparatus for use in a punch press having a die receiving bed and a ram reciprocable toward and away from said bed, said apparatus comprising a die plate member securable to said bed and a punch holding member comprising a pair of vertically spaced generally horizontal plates, vertical guide pins fixed to one of said members and slidably engageable with the other, yieldable means normally retaining the punch holding member in an elevated position, a plurality of punching units each comprising a stripper sleeve carried by the lower plate of the punch holding member, a punch extending through said stripper sleeve and having an enlarged upper head portion vertically slidable in the upper plate of the punch holding member and projecting thereabove to be engaged by said reciprocable ram, and a compression coil spring surrounding the punch and engaging at its upper end against said punch head portion and at its lower end against the stripper sleeve.

4. Sheet material punching apparatus for use in a punch press having a die receiving bed and a ram reciprocable toward and away from said bed, said apparatus comprising a die plate member securable to said bed and a punch holding member comprising a pair of vertically spaced generally horizontal plates, means guiding said members for movement toward and away from each other, yieldable means normally retaining the punch holding member in an elevated position, a plurality of punching units each comprising a stripper sleeve carried by the lower plate of the punch holding member, a punch extending through said stripper sleeve and having an enlarged upper head portion vertically slidable in the upper plate of the punch holding member and projecting thereabove to be engaged by said reciprocable ram, and a compression coil spring surrounding the punch and engaging at its upper end against said punch head portion and at its lower end against the stripper sleeve.

5. Sheet material punching apparatus for use in a punch press having a die receiving bed and a ram reciprocable toward and away from said bed, said apparatus comprising a die plate member securable to said bed and a punch holding member comprising a pair of vertically spaced generally horizontal plates, vertical guide pins fixed to one of said members and slidably engageable with the other, compression spring means acting between said members to normally retain the punch holding member in an elevated position, a plurality of punching units each comprising a stripper sleeve carried by the lower plate of the punch holding member, a punch extending through said stripper sleeve and having an enlarged upper head portion vertically slidable in the upper plate of the punch holding member and projecting thereabove to be engaged by said reciprocable ram, a compression coil spring surrounding the punch and engaging at its upper end against said punch head portion and at its lower end against the stripper sleeve, and releasable means at the upper side of the upper plate of the punch holding member engageable with the head portion of said punch to limit upward movement thereof.

6. Sheet material punching apparatus for use in a punch press having a die receiving bed and a ram reciprocable toward and away from said bed, said apparatus comprising a die plate member securable to said bed and a punch holding member comprising a pair of vertically spaced generally horizontal plates, means guiding said members for movement toward and away from each other, yieldable means normally retaining the punch holding member in an elevated position, a plurality of punching units each comprising a stripper sleeve carried by the lower plate of the punch holding member, a punch extending through said stripper

lower plate of the punch holding member, a punch extending through said stripper sleeve and having an enlarged upper head portion vertically slidable in the upper plate of the punch holding member and projecting thereabove to be engaged by said reciprocable ram, a compression coil spring surrounding the punch and engaging at its upper end against said punch head portion and at its lower end against the stripper sleeve, and releasable means at the upper side of the upper plate of the punch holding member engageable with the head portion of said punch to limit upward movement thereof.

10

7. Sheet material punching apparatus for use in a punch press having a die receiving bed and a ram reciprocable toward and away from said bed, said apparatus comprising a die plate member securable to said bed and a punch holding member comprising a pair of vertically spaced generally horizontal plates secured to each other for ready detachability, vertical guide pins fixed to one of said members and slidably engageable with the other, compression spring means acting between said members to normally retain the punch holding member in an elevated position, a plurality of punching devices associated with said apparatus each comprising a stripper sleeve carried by the lower plate of the punch holding member, a punch extending through said stripper sleeve and having an enlarged upper head portion vertically slidable in the upper plate of the punch holding member, and a compression coil spring surrounding the punch and engaging at its upper end against said punch head portion and at its lower end against the stripper sleeve.

15

8. Sheet material punching apparatus for use in a punch press having a die receiving bed and a ram reciprocable toward and away from said bed, said apparatus comprising a die plate member securable to said bed and a punch holding member comprising a pair of vertically spaced generally horizontal plates secured to each other for ready detachability, means guiding said members for movement toward and away from each other, compression

20

25

30

spring means acting between said members to normally retain the punch holding member in an elevated position, a plurality of punching units each comprising a stripper sleeve carried by the lower plate of the punch holding member, a punch extending through said stripper sleeve and having an enlarged upper head portion vertically slidable in the upper plate of the punch holding member and projecting thereabove to be engaged by said reciprocable ram, and a compression coil spring surrounding the punch and engaging at its upper end against said punch head portion and at its lower end against the stripper sleeve.

9. Sheet material punching apparatus for use in a punch press having a die receiving bed and a ram reciprocable toward and away from said bed, said apparatus comprising a die plate member securable to said bed and a punch holding member comprising a pair of vertically spaced generally horizontal plates, vertical guide pins fixed to one of said members and slidably engageable with the other, compression spring means acting between said members to normally retain the punch holding member in an elevated position, a stripper sleeve carried by the lower plate of the punch holding member and extending therebelow to engage and hold a work sheet, a punch extending through said stripper sleeve and having an enlarged upper head portion vertically slidable in the upper left of the punch holding member, and a compression coil spring surrounding the punch and engaging at its upper end against said punch head portion and at its lower end against the stripper sleeve.
